W. F. BRÜGMANN,
PRINTING PLATE MOUNTING.
APPLICATION FILED JULY 19, 1915.

Patented Dec. 6, 1921.

2 SHEETS—SHEET 2.

UNITED STATES PATENT OFFICE.

WILLIAM F. BRÜGMANN, OF EVANSTON, ILLINOIS, ASSIGNOR TO PRINTING UTILITIES COMPANY, A CORPORATION OF DELAWARE.

PRINTING-PLATE MOUNTING.

1,399,047.

Specification of Letters Patent.

Patented Dec. 6, 1921.

Application filed July 19, 1915. Serial No. 40,640.

To all whom it may concern:

Be it known that I, WILLIAM F. BRÜGMANN, a citizen of the United States, residing in the city of Evanston, county of Cook, 5 and State of Illinois, have invented certain new and useful Improvements in Printing-Plate Mountings, of which the following is a specification.

My invention relates to improvements in 10 printing plate mountings, and more particularly refers to apparatus which involves the elimination of the wooden backing long employed on electrotype and other printing plates. This invention relates to improvements upon my previous United States Patent No. 983,675, granted February 7, 1911.

Among the salient objects of the invention are, to provide a mounting block for a printing plate with an improved form of hook or 20 clamp for securing the plate on the block; to provide improved means for detachably securing the hook or clamp in various positions of adjustment in a groove formed in the face of the mounting block; to provide 25 improved mechanism affording micrometer adjustment of the hook or clamp lengthwise of the groove; to provide means for locking said mechanism in the adjusted position against accidental movement and preventing 30 the printing plate from becoming loosened from the mounting block owing to the jar and vibration incidental to the operation of the printing press; and in general to provide improved devices for mounting printing plates.

In the drawings which accompany this application—

Figure 1 is a plan view of the bed of a press;

Fig. 2 is an enlarged side elevation of a 40 stationary catch in the diagonal groove of a printing block, parts of which are broken away;

Fig. 3 is a section taken on the line 3—3 45 of Fig. 2;

Fig. 4 is a section taken on the line 4—4 of Fig. 2;

Fig. 5 is a section taken on the line 5—5 50 of Fig. 4;

Fig. 6 is a section taken on the line 6—6 of Fig. 5;

Fig. 7 is an enlarged fragmentary plan view of the stationary catch and block illustrated in Fig. 2;

Fig. 8 is an enlarged plan view of a block

and an adjustable micrometer catch mounted on said block;

Fig. 9 is a fragmentary section showing the manner in which the insertion of the key operates to disengage the micrometer detent; 60

Fig. 10 is a side elevation of the catch shown in Fig. 8;

Fig. 11 is a section taken on the line 11—11 of Fig. 10;

Fig. 12 is a section taken on the line 12—12 65 of Fig. 11, and showing a catch in position in the groove of a mounting block, certain parts of which are broken away;

Fig. 13 is a section taken on the line 13—13 of Fig. 12;

Fig. 14 is an end view of the catch shown in Fig. 10, looking from the left-hand of said figure;

Fig. 15 is a section taken on the line 15—15 70 of Fig. 12, the block being omitted.

The base plate of my improved mounting is preferably composed of a series of square units having diagonal grooves therein for insertion of the catches, these grooves being somewhat similar to those shown in my previous Patent No. 983,675. In Fig. 1 I show a base made up of six of these units 40 which for purposes of lightness I preferably construct of aluminum. The diagonal grooves 41 in these units, as shown best in Fig. 3, 75 are wide enough to admit the bodies of various catches or clamps utilized in connection with the metal mounting base. Slightly below the open top of the groove the latter is enlarged so as to furnish a pair of opposed 80 shoulders 42 with which coöperate engaging devices carried by the various types of catches for preventing the same from rising out of the grooves. Some distance below the shoulders 42 I mill or broach out the 85 opposite sides of the grooves and in one side I insert a hardened steel wear strip 43, and in the other side of the groove directly opposite I insert a somewhat similar hardened steel wear strip 44 which, however, is 90 provided with rack teeth 45 projecting into the slot. The bottom of each of the diagonal grooves 41 is preferably located a substantial 95 distance below the lower edges of the rack teeth 45 so as to allow a space for accumulations of dirt or oily matter to run into or accumulate without interfering with the operation of the rack teeth or other parts.

The strip 43 and rack bars 44 are held and located in the units of the base by means of 100

105 110

transverse pins 46 (see Figs. 3 and 7). The units 40 which, as previously stated, are preferably made of aluminum, are cast hollow between the grooves 41, as shown at 47 in Fig. 3, in order to save metal and further to enhance the lightness of the construction.

The units 40 are maintained in register with each other by means of dowel holes 48 (see Fig. 8) and dowel pins 49 (see Fig. 7). 10 In order to prevent interference by the dowel pins 49 when locking the complete base in the form by means of the usual devices employed for that purpose, I construct the same in such a manner that when pressure is applied to the ends of the dowel they will enter and sink flush with the outer edges of the units. To this end I make the dowel pins 49 with enlarged inner ends 50 which are adapted to slide in cylindrical holes bored 15 in the plate blocks, the pins being normally forced outwardly by means of coil compression springs 51 inserted behind the rear faces of said enlargement 50. The pins 49 are prevented from flying out of the bores by 20 means of sleeves 52 forced into the ends of said cylindrical bores after the springs and pins have been inserted.

Describing the stationary catch 53, the same being illustrated in Figs. 1 to 7, inclusive, this consists of a main body portion, rectangular in longitudinal cross-section, the upper end being of the proper width to fit snugly in the open end of the groove 41. The lower end of the body portion is reduced 35 in width by milling off each side, as shown at 54, so as to make room for the teeth 45 of the rack bar. Both sides of the catch are cut away in this manner so that it will make no difference which way the stationary catch 40 may be inserted in the groove.

Describing the means for locking the stationary catch against longitudinal movement in the groove, in one end of the body I drill a hole within which is a cylindrical bushing 45, 55 having an enlarged shoulder head portion 56 at its lower end, its upper end being threaded, as shown at 57, in order to enter a threaded aperture in the lower end of the jaw 58. The lower end of the cylindrical 50 aperture in the body portion is enlarged to admit the shoulder portion 56 on the bushing 55 and so prevent upward movement of said bushing and the jaw secured thereto. I provide a slight amount of clearance between the 55 lower edge of the jaw 58 and the upper edge of the body portion so as to allow the jaw 58 to swivel freely on its bushing mounting. The upper edge of the jaw 58 is bored out and countersunk to admit the enlarged upper 60 head of the pin 59, which slides freely in the bushing 55, and the lower end of said pin 59 is provided with a conical enlargement 60 driven and firmly secured upon a reduced lower portion 61 of the pin 59. The extreme 65 lower end of said pin 59 is screwed tightly

into a block 62 which slides in a slot 63 cut transversely across the lower end of the body portion of the catch. Said block 62, as shown in Figs. 2, 3, and 6, has projecting side teeth 64 which engage the teeth 45 of the rack 70 bar when the block 62 is depressed. The pin 59, as to its upper end, is long enough to allow a substantial amount of vertical movement of the sliding block 62 before the head of the screw strikes the upper end of the 75 bushing 55. When the pin 59 is in the position shown in Fig. 5, the lower edges of said teeth 64 are high enough to avoid the upper edges of the rack teeth 45 so as to allow the stationary catch to slide freely 80 along the groove 41. When, however, the pin 59 is depressed, the block 62 slides downwardly and the teeth 64 engage the rack teeth 45 and securely lock the stationary catch in the groove and prevent sliding movements 85 thereof. A great advantage of the stationary catch above described is that it may be inserted and slid along the block into any location before it is locked into position. This is a very great convenience in actual practice. 90

Describing the means for locking the stationary catch against vertical movement in the groove 41, below the level of the shoulders 42 I mill a horizontal slot 65 in the catch body so as to admit a pair of horizontally swinging locking members 66 and 67 which pivot scissors-fashion upon a vertical pin 68 inserted from the upper side of the catch body and threaded into the lower portion, as at 69. The rear ends 95 66' and 67' of said locking members lie in horizontal side grooves formed in the body of the catch above the slot 63, and the adjacent inner edges of said portions 66' and 67' are cut out so that in conjunction with 100 each other they constitute a circular pocket or bearing for the conical collar 60. As shown in Fig. 6, the inclination of said circular bearing notches in the members 66' and 67' corresponds with the inclination of 105 the cone 60, so that when the latter is depressed the parts 66' and 67' separate and cause the ends of the members 66 and 67 to engage below the shoulders 42 of the groove 41 and thus prevent withdrawal of the catch. 110 In order to prevent loosening of the catch, due to improper outward vertical movements of the pin 59, the upper end of the cone 60 has a short cylindrical portion, as shown at 69a, so that when the pin 59 is 115 completely depressed the said cylindrical portion 69a fits between corresponding straight portions 70 and 71 on the adjacent edges of the members 66' and 67' so that there is no tendency for the cone to rise. Although one side of the teeth 64 engage the 120 rack bar teeth 45, it should be understood that the outer edges of the teeth on the other side of the member 62 slide upon the hardened steel wear strip 43, so that there 125

is absolutely no tendency for the stationary catch to tip in a transverse direction, whatever may be the location of the printing plate with reference to the jaw. The catch 5 is released by inserting the point of any convenient tool, such as a small screw-driver, in one of the depressions 73 and then prying up the head of the screw 59, thereby permitting the spring 71^a to retract the parts 10 66 and 67. In order to facilitate engagement of the teeth 64 with the rack bar teeth 45, the upper edges of the latter are beveled off, as shown at 72.

The device is exceptionally rapid to manipulate, since the catch is first located in 15 the groove 41, and then a single movement of the pin 59 locks the catch against longitudinal movement and against upward movement. The spring 71^a, which tends to 20 close the scissors members 66 and 67, causes the pin 59 to be resiliently forced upwardly away from the catch body, so that after the catch body has been moved into approximately correct position, the entrance of the 25 teeth 64 into the rack may be tested by lightly pressing down upon the head of said pin 59 to see if the teeth are in proper register.

Heretofore great difficulty has been experienced in lining up the stationary catches and in locking them in their proper positions on the foundation blocks. To eliminate this difficulty, I locate all of the racks 30 44 with their teeth in exactly the same position relative to their distance from one edge of the block; so that the center of, for instance, the fourth rack tooth in any groove of the block will always be exactly the same distance from the lateral edge of the unit. 35 I also inscribe on the surface of the block a series of parallel guide lines 73^a and a second set 74^a crossing the first set at right angles, both sets of lines dividing the surface of the unit into a definite number of 40 parts, so that the guide lines of adjacent blocks will be continuations of each other. A convenient spacing for these lines is one pica, and I prefer to cut certain lines deeper, as shown at 75, so as to make the line spacings readily distinguishable. By the aid 45 of these lines and by virtue of the fact that the racks are all located in precisely the same relative longitudinal position in the base-blocks, and the stationary catches being 50 all interchangeable, it is a simple matter to line up the catches on the foundation. In order still further to facilitate the lining up of the stationary catches on the foundation, I construct the racks with their teeth 55 spaced apart such a distance longitudinally that their positions are definite with respect to the guide lines inscribed on the surface of the plate foundation. For instance, I may make the racks with a tooth 60 spacing such as to cause the stationary catch 65 to assume positions coincident with the guide lines and at a different intermediate position between said guide lines.

Describing the details of the adjustable micrometer catch 74, illustrated in Figs. 8 to 70 15, inclusive, the body portion 75 of said catch is a solid piece of steel or similar metal, the upper portion of which is of the proper width to slide in the groove 41 and fits snugly 20 between the overhanging upper edges thereof. The catch is locked as against upward movement out of the groove 41 by means of a pair of cam bars 76 which are mounted to 25 slide in a pair of oppositely disposed horizontal longitudinal grooves in the sides of the body portion 75, the upper edges of the cam bars being the right height to engage under 30 the overhanging shoulders 42 when said cam bars are in their proper position to effect such locking engagement. In order to slide the 35 cam bars 76 into and out of engagement with the shoulders 42, I mount in one end of the body portion 75 a short flat lever 77 which, intermediate its ends, is pivoted upon a fixed 40 horizontal pin 78 transversely disposed in the end of the body portion 75, the center of 45 which is slotted out, as shown at 79, in order to admit said lever 77. In the lever 77, toward the upper end, is securely fixed a transverse pin 80 which projects outwardly from 50 each side of the lever 77 a sufficient distance to engage a pair of notches 81 (see Fig. 11) 55 in the ends of the cam bars 76. In the shelves 82 of the body portion 75 constituting the bottom sides of the grooves in which 60 slide the cam bars 76, I fix two pairs of fixed pins 83, the upper ends of said pins projecting 65 vertically into the said grooves a sufficient distance to enter two pairs of obliquely 70 disposed grooves or recesses 84 milled in the under sides of the cam bars 76. It is manifest 75 that if the cam bars 76 be reciprocated longitudinally by the transverse pin 80 when the lever 77 is rocked on its pivot, the result will be that said bars will be compelled to 80 move in an oblique direction corresponding with the obliquity of the grooves 84. Thus, the cam bars 76 will be forced inwardly or outwardly so as to engage or disengage the shoulders 42, as the case may be. On the upper 85 end of the lever 77 is a longitudinally disposed finger piece 85, the inner end 86 of which is beveled so as to permit the insertion of the finger nail or any convenient tool under the end of said plate 85 to operate the lever 77. In the full-line position of said finger piece 85, shown in Fig. 10, the cam bars 76 are thrust outwardly to engage the shoulders 42, as shown also in Figs. 11 to 15. In the dotted-line position of the lever 77 and 90 finger piece 85 the cam bars are withdrawn with their edges flush with the sides of the body portion 75 so that the catch may be withdrawn vertically out of the groove 41. In order to make the lever 77 self-locking in 95

either position and prevent rattling or displacement of the lever 77 by the movement of the press, I insert in the lower end of the lever 77 a thimble 88 which slides in a transverse cylindrical bore 89 and is forced outwardly by means of a small coil compression spring 90 which causes the rounded end of the thimble to enter either one of a pair of round holes 91 and 92 drilled through the 5 sides of the slot 79. In the dotted-line position, the end of the thimble 88 engages the inner end of the hole 92, and in the full-line position it engages the hole 91, as shown in Fig. 10. When the catch 74 is inserted in 10 the groove, it is prevented from falling to the bottom of the same by one of the shoulders 15 87 striking the upper edges of the teeth 45 of the rack bar 44 (see Fig. 13).

Describing the plate-clamping mechanism, 20 in the body portion 75 between the center of the catch and the end which is remote from the lever 77, I drill out a vertically extending cylindrical hole within which is located a hub 94 having an upper enlargement 95 25 which is rectangular as to its cross-section and fits in a corresponding enlargement in the upper end of said cylindrical aperture. The upper side of said enlargement 95 is flush with the upper surface of the body portion 75 and is extended as to its upper end outwardly at each side so as to constitute a plate-clamping jaw 96. The said jaw 96 is beveled so as to fit the regular printing plates, and its hub 94 swivels freely in the 30 body portion 75 so that the jaw will accommodate itself to the edge of the printing plate. In order to prevent the hub 94 from rising out of its bearing, the lower end of said bore is enlarged from the under side, as 35 shown at 97, and the lower end of the hub is drilled out and threaded to admit a headed, threaded bushing 98 which forms a unit with the hub 94 and thus prevents the withdrawal of the jaw from the body portion.

40 Describing the mechanism for effecting micrometer adjustment of the catch in the grooves 41, the under side of the catch is cut away so as to admit a worm 99 which rotates upon the stem 100 of a pin 101 arranged 45 longitudinally in the center of the bottom part of the body portion and supported by a shouldered nut 102 which enters a longitudinal hole 103 in the end of the body portion and screws upon the threaded end of the 50 stem 100. The other end of said pin 101 is supported in a longitudinal bore 104 at the other end of the body portion. The large end of the pin 101 is formed with an enlarged head 105, the upper side of which is 55 flattened, as shown at 106, and engages an overhanging shoulder 107 at the end of the body portion and so prevents the pin 101 from turning.

60 The inner end of the large diameter pin 101 is flattened by milling off its upper side,

as shown at 108, in order to form a seat for the lower end of an axially vertical bevel pinion 109 which is co-axial with the hub 94 and rotates in a circular recess below the threaded bushing 98. The bevel pinion 109 70 is pressed upwardly by a coil spring 108^a located in a small countersink 109^a in the bottom of the pinion. In the jaw 96 and the bushing 98 is a concentric drilled hole 110 of a sufficient diameter to admit a square 75 key which is adapted to enter a square hole 111 in the center of the bevel pinion 109. The end of the worm 99 is extended and has bevel teeth 112 cut upon it to mesh with the teeth 113 on the oblique lower face of the 80 bevel pinion 109. It is manifest that when the bevel gear 109 is rotated by a suitable key inserted in the bore 110, the intermeshing bevel teeth will cause the worm 99 to revolve, and the threads of the latter which engage the teeth 45 of the rack bar 44, as shown in Fig. 13, will cause the catch to move bodily longitudinally in the groove 41, thereby forcing the jaw 96 toward or away 85 from the edge of the printing plate. 90

The pressure transmitted through the catch and worm to the rack teeth is of such a character as tends to separate the two lower depending ends of the catch body longitudinally. This separating tendency, due 95 to the pressure of the worm 99, is substantially obviated and the catch body is thus strengthened by reason of the fact that the longitudinal pin 101 ties the two ends of the catch body together and receives a substantial part of the stress. I also prefer to make the diameter of the stem portion 100 of said pin a substantial amount less than the diameter of the longitudinal hole in the worm 99 so as to allow the worm to assume 100 a position where its periphery on the side opposite the rack teeth is in bearing contact with the wear strip 43, thereby relieving the catch body of transverse strain and preventing it from tipping. I prefer to accentuate 105 the crowding effect of the worm 99 and its consequent pressure upon the face of the wear strip 43 by beveling the teeth of the rack slightly, as shown at 112^a in Fig. 8. The effect of this is to hold the worm 110 frictionally in adjustment after being set, and prevents its loosening.

115 It has been found that some times dirt or grit has a tendency to collect or deposit on the mating faces of the respective block units, thereby preventing the same from being forced into proper intimate contact with each other. The space thus present between the edges of the blocks causes difficulty 120 when the worm of the micrometer catch attempts to pass out of engagement with the end of the rack in one block and into engagement with the adjacent end of the rack in the corresponding groove of the contiguous block. I overcome this difficulty by 125 130

shaving off the sides of a few teeth at the ends of the racks, thereby reducing the tooth thickness and increasing the tooth space so that the threads of the worm will be properly engaged and the worm will pull itself into mesh with the adjacent rack; this being indicated at 113^a in Fig. 8.

In Figs. 9, 10, 12 and 13 I have illustrated a device which I have found to be very advantageous in preventing the loosening up of the micrometer catch owing to improper movements of the worm caused by the vibration of the press. This comprises a vertically swinging dog 150 which is hung from a horizontal pin 151 and is located in a vertical slot 152. The lower end of said dog 150 projects obliquely under the bevel wheel 109, the teeth of which are engaged by the sharpened edge 153, the dog being pressed toward the bevel wheel by a small coil compression spring 154 inserted in a longitudinal drilled hole 155 bored in the body of the catch. The pin 101 is slotted by milling, as shown at 156, in order to admit the lower end of said dog, and the body of the pin 101 is also provided with a vertical hole (not shown) which admits the reduced lower end of the key 157 when the latter is inserted for the purpose of adjusting the catch as shown in Fig. 9. It will be observed by reference to Fig. 9 that when the key 157 is inserted, the reduced stem or tip 158 engages the point 159 of the dog and rocks the latter on its pivot slightly, thus forcing the edge 153 out of engagement with the teeth of the bevel gear and permitting the latter to be rotated by the key. As soon as the catch is adjusted and the key 157 is withdrawn, the dog 150 is permitted to rock on its pivot, the edge 153 reengaging the teeth of the bevel gear 109 and securely locking the same against rotary movement.

Although I have described what may be considered a preferred embodiment of my invention, it should be understood that the mechanical details and arrangement may be modified widely without departing from the spirit of the invention; hence, I do not wish to be limited, except as specified in the appended claims.

I claim—

1. In a printing plate mounting, the combination of a foundation having an undercut groove in its upper surface, a plate-clamping catch having a body insertible in, and slidable along, said groove, means carried by, and movably mounted on, said body for locking said body against movement out of said groove and engageable with the under-cut surfaces of said groove at points spaced longitudinally of said groove, a member carried by said body for controlling said locking means and means in the groove and on the block meshing together, when the
2. In a printing plate mounting, the combination of a foundation block having a groove in its upper surface, said groove having opposed overhanging shoulders, a plate-clamping catch provided with a body insertible in said groove and slidable between said shoulders, a pair of transversely movable opposed locking members capable of being simultaneously spread apart to engage under said opposed shoulders and thereby lock said body in said groove, a member carried by, and permanently mounted on, said body for controlling said locking members and relatively adjustable intermeshing means on the wall of the groove and the body of the plate clamping catch for locking said catch against sliding movement in the groove.
3. In a device of the class described, the combination of a foundation block having a channel in its upper surface, a rack associated with said channel, a plate clamping device provided with means coöoperating with the rack to effect micrometric movement of said device along the channel, means on the block and separable locking members on the clamp having a spreader adjustable to engage and disengage the locking members with said means on the block for locking the clamping device against transverse movement out of the channel and permitting sliding movement therein, and a spring lock for holding said spreader in its positions of adjustment.
4. In a device of the class described, the combination of a foundation block having a channel in its upper surface, a rack secured in said channel, a plate clamping device freely insertible in said channel and provided with means coöoperating with the rack to effect micrometric sliding movements of the clamp along the channel, means in the channel and separable members on the clamp adapted to engage said means to lock the clamp against transverse movement out of and permit sliding of said device in the channel, a manually operable spreader for expanding and retracting said members, and a spring for locking said spreader to hold said members in either the expanded or retracted position.
5. In a device of the class described, the combination of a foundation block provided with a channel in its upper surface, a stationary rack associated with said channel, a plate-clamping device provided with means coöoperating with the rack to effect micrometric sliding movements of said device along the channel, said channel being formed with over-hanging portions, a pair of parallelly-disposed locking bars on the opposite

- longitudinal sides of said catch movable at will to effect lateral engagement with said over-hanging portions to prevent removal of said clamp out of said channel, and means 5 on said catch for controlling said bars.
6. In a device of the class described, the combination of a foundation plate provided with a channel in its upper surface, a stationary rack associated with said channel, 10 a plate-clamping device provided with means coöperating with the rack to effect micrometric sliding movements of said device along the channel, said channel being formed with over-hanging portions, a pair of parallelly-disposed locking bars on the opposite longitudinal sides of said catch, and a common actuating member carried by said catch and operable at will for effecting bodily movements of said bars to engage the same 15 with said over-hanging portions to prevent transverse movement of said clamp out of said channel.
7. In a device of the class described, the combination of a foundation plate provided 20 with a channel in its upper surface, a stationary rack associated with said channel, a plate-clamping device provided with means coöperating with the rack to effect micrometric sliding movements of said device along the channel, said channel being formed 25 with over-hanging portions, a pair of parallelly-disposed locking bars on the opposite longitudinal sides of said catch, and cam mechanism mounted on said catch for effecting at will symmetrical bodily movements 30 of said bars to engage the same with said over-hanging portions for preventing movement of said clamp out of said channel.
8. In a device of the class described, the combination of a foundation plate provided 35 with a channel in its upper surface, a stationary rack associated with said channel, a plate-clamping device provided with means coöperating with the rack to effect micrometric sliding movements of said device along the channel, said channel being formed 40 with over-hanging portions, a pair of parallelly-disposed locking bars on the opposite longitudinal sides of said catch, and a common actuating member movably mounted on, 45 and carried by, said catch, and operable at will for effecting symmetrical bodily movements of said bars to engage the same with said over-hanging portions for preventing 50 movement of said clamp out of said channel.
- 55 9. In a printing plate mounting, the combination of a foundation block having a channel in its upper surface, a rack mounted in said channel, a printing plate clamp having a body portion with spaced depending ends integral therewith and slidably mounted in said channel, a shaft supported in and locking said ends together, a worm wheel rotatably mounted on said shaft interme- 55 diate of said depending ends and engaging 65 said rack, and gearing for actuating the worm to coöperate with the rack and move the clamp along the groove.
10. In a printing plate mounting, the combination of a foundation block composed of 70 a plurality of contiguously disposed units, said units being provided with racks terminating substantially at the boundaries thereof, the racks of adjacent units being longitudinal continuations of each other, a catch 75 body provided with means coöperating with the racks for effecting micrometric movements of said catch body and adapted to travel across the boundary line between adjacent units, said racks having adjacent end 80 teeth, reduced in thickness, whereby said coöperating means is capable of passing out of engagement with the end of one rack and into engagement with the end of the adjacent rack, in the event of inaccuracies in 85 assembly of said units.
11. In a printing plate mounting, the combination of a plate clamp, means for effecting micrometric movements of said clamp including a rotatable member operable by a 90 removable key, and a locking member coöperating with the rotatable member to lock the clamp in various positions of adjustment and adapted to be disengaged by the insertion of said key in said rotary member. 95
12. In a printing plate mounting, the combination of an adjustable plate clamp, a block for supporting the printing plate, gearing for effecting micrometric movement of said clamp with reference to said block, 100 said gearing including a rotary member operable by a removable key insertible in said rotary member, and a locking member adapted to lock the rotary member in various positions of adjustment and adapted to 105 be disengaged by the insertion of said key.
13. In a printing plate mounting, the combination of a grooved block, a plate-clamping catch located in said groove, a train of gearing for effecting micrometric movements of said catch in said groove, said gearing including a rotatable member operable by a removable key, a pivoted locking member normally engaging said rotatable member and preventing rotary movement thereof and means for holding the locking member disengaged from the rotatable member during operation of the latter. 110
14. In a printing plate mounting, the combination of a grooved block, a catch in said groove, a train of gearing for effecting micrometric movements of said catch in said groove, said gearing including a toothed rotary member carried by said catch and adapted to be operated by a key insertible in said catch, and a pivoted locking member adapted to engage with the teeth of the ro- 115

tary member to lock the catch in various positions of adjustment and adapted to be released by the insertion of said key in said catch.

5. 15. In a printing plate mounting, the combination of a foundation block having a groove in its upper surface, an adjustable catch located in said groove, means for locking said catch in said groove against vertical movement out of said groove, a rack associated with said groove, a rotary member carried by said catch coöperating with said rack and rotatable to effect micrometric movements of said catch in said groove, a second rotary member coöperating with said first rotary member and adapted to rotate the same, said second rotary member being provided with a central hole for the insertion of a removable key, a pivoted locking member normally engaging the periphery of one of said rotary members but adapted to be released by the insertion of said key in said second rotary member, and a spring normally forcing said locking member into engagement with the periphery of said rotary member.
10. 16. In a printing plate mounting, the combination of a grooved foundation block, a plate-clamping catch located in said groove, means for locking said catch against movement in said groove, a rack associated with said groove, a worm with its axis parallel with said groove and rack and carried by said catch for effecting micrometric movement of said catch in said groove by co-operation with said rack, a bevel gear having its axis vertical and mounted to rotate in said catch and coöperating with said

worm to effect rotary movement thereof, said bevel gear having a central keyed hole 40 therein for the insertion of a removable key, a pivoted locking member swinging in a vertical plane and having its lower end extending below said bevel gear and adapted to be pushed aside to rock said locking member on its pivot when the key is inserted in said bevel gear to rotate the same, and a spring normally forcing said locking member into engagement with the periphery of said bevel gear.

15. 17. In a printing plate mounting, the combination of an adjustable plate-clamping device, a member for adjusting said plate-clamp whereby micrometric movements of said plate-clamp may be effected, and means 55 for locking said adjusting member, said means being adapted to be withdrawn and held from engagement with said member during the operation of the latter.

20. 18. In a printing plate mounting, the combination of an adjustable plate-clamping device, a member for adjusting said plate-clamp whereby micrometric movements of said plate-clamp may be effected, means 60 movable with said clamp for locking said adjusting member whereby improper movements of said catch are prevented, and a key for operating said member adapted to release and hold said means from engagement with said member during operation of the latter.

WILLIAM F. BRÜGMANN.
